F. R. PROCUNIER
LIQUID LEVEL INDICATOR

Filed Dec. 15, 1923

Frank R. Procunier

UNITED STATES PATENT OFFICE.

FRANK R. PROCUNIER, OF CHICAGO, ILLINOIS, ASSIGNOR TO OTTO RABE, OF CHICAGO, ILLINOIS.

LIQUID-LEVEL INDICATOR.

Application filed December 15, 1923. Serial No. 680,789.

This invention relates to an indicator in the nature of an alarm adapted to afford an audible warning of diminution in the volume of a liquid contained within a receptacle. It may be advantageously employed in many different capacities, notably in connection with the fuel tank of an automobile.

It is a primary object of my invention to provide an alarm device of this general kind, the components of which constitute a self-contained unit; a device which may, if desired, be connected with the filling spout of a tank to serve additionally as a cap therefor; a device whose operation may be regulated, as desired, so as to audibly indicate the presence of a minimum predetermined volume of liquid within a receptacle; and a device whose operation may be shut off at will, should such be desired.

For purposes of exemplification, the accompanying drawing presents an embodiment of my invention in the manner following:

Figure 1 is an end view of a conventional automobile fuel tank to which the present device is applied;

Fig. 2 is an enlarged vertical section through the device, showing its relation to the adjacent tank portions with which it co-operates;

Fig. 3 is a transverse section therethrough taken approximately on line 3-3 of Fig. 2; and

Fig. 4 shows a side elevation view thereof.

The device is here shown in relation to a fuel tank A which may be of the conventional type used in automobiles. It includes a bottom 5 and a top 6 having a threaded filling spout 7 to which a closure cap is ordinarily applied. For convenience in installation the present device may be advantageously associated with such a spout; although the purposes of my invention would be fully served by locating the indicator elsewhere.

The several components of my invention are comprised in a self-contained unit having a chambered head B connected with a depending guide C, preferably in the form of a cylindrical body, as shown. Formed on the head is a downwardly extending neck 10 threaded to engage with the spout 7 for the purpose of securing the device in a fixed relation to the tank. The head is prefer-

ably connected to the guide member in a removable manner as by means of one or more pins 11 extended inwardly from its neck, each engaging within a bayonet cam slot 12 which is provided in the upper end of the body. By some such means as this, the head and body of the device are connected in unitary relation.

Extending upwardly from the head is a circular flanged wall 15 surrounded by a slip-ring or rotatable collar 16 whose outer side is preferably serrated for convenience in gripping. The head is further chambered to accommodate an alarm device which preferably comprises a housing 20 over which is mounted a dome-shaped bell 21, a suitable spring actuated apparatus for ringing the bell being enclosed in the intervening space. Such an apparatus may be of any conventional kind, including a spring 22 adapted to be placed under tension by rotation of the bell, and connected through suitable gearing, an escapement, etc., with a hammer 23 which is adapted to vibrate against the bell. As such a bell ringing apparatus is well known, no further description thereof is deemed necessary. It should be noted, however, that this alarm device has a self-contained operating mechanism, and may be secured conveniently in place by the use of one or more screws 24, as shown.

Referring now to Fig. 3, I have shown a slot 25 formed through the upper head wall 15, and extending through this slot is a finger 26 carried by the slip ring 16. The inner end of this finger is located relative to the hammer in a manner to interfere with its operation whenever the ring is so rotated as to move the finger to the position indicated by dotted lines. Such a relationship of the parts is contemplated whenever the ring is manipulated to unscrew the head from the spout preliminary to removal of the device from the tank.

I also provide for controlling the alarm means which will be responsive to withdrawal of liquid from the tank beyond a minimum predetermined volume, and for this purpose employ a rod or wire 30 which extends centrally through the guide member to connect near its lower end with a float 31. As shown, the float is provided at one end with an extension 32 wherein is secured a set-screw 33 adapted to engage the rod for the purpose of holding the float in a fixed

position of adjustment thereupon. Suitable markings 34 may be provided on the rod to assist in determining the correct position of the float in relation to the minimum volume of liquid within the tank desired for operation of the alarm. Near its upper end the rod is laterally extended, as at 35, and then is bent again at 36 to present an upper extremity 37 which passes through a suitable opening in the head to lie adjacent the hammer 23 (see Fig. 3).

As shown, the guide member is preferably in the form of a closed cylindrical body open only at its lower end where an inwardly turned flange 40 is provided. Arranged adjacent the under side of this flange I have represented a valve disk 41 formed with one or more openings 42 of restricted size. In the central portion of the disk is a nipple 43 through which is guided the lower end of the rod 30. The disk may be held centrally with reference to the body as by means of a plurality of upwardly extending arms 44 each disposed adjacent the inner face of the flange 40, an outward extension 45 being provided at the extremity of each arm, as shown. By some such means as this, the disk is limited in its sliding movements away from the flange 40. Always, however, the disk is in axial relation with respect to the float so as to properly guide the lower extremity of the rod 30. Upon the lower side of the disk may be carried a coiled spring 46 adapted to rest against the tank bottom so as to yieldingly hold the valve disk against its seat.

An indicator answering to the preceding description may be conveniently secured within a suitable spout that is preferably located on the upper side of a tank or receptacle. In screwing the head to final position, the slip ring 16 is normally rotated to remove the finger 26 from engagement with the hammer 23 so that the alarm will be free to operate when the volume of liquid has diminished to the predetermined point. With insertion of the device within the tank, the spring 46 which is rested against the tank bottom, as shown in Fig. 2, acts to hold the valve disk to its seat, so that communication with the body interior may only be through the restricted opening 42. The float will remain in the uppermost position permitted by engagement of the rod bend 36 with the head, this relationship of the parts continuing until a sufficient quantity of liquid has been drawn from the tank to cause a lowering of the float. The rod extremity 37 is also held constantly in adjacent relation to the hammer so as to prevent its operation under the action of the spring 22. When the float recedes from this uppermost position, the rod 30 will also be lowered with the result that its upper extremity is then clear of the hammer. At this

moment, the bell ringing apparatus will commence to operate. The alarm thus given will be informative of a diminution in volume of liquid within the tank to the point which has been predetermined by the adjustment of the float upon the rod.

Should the device be installed in a filler spout, as represented in the drawing, its removal will be required for the replenishment of the liquid supply. It is desirable that the liquid which supports the float within the chambered guide member should be quickly drained therefrom and this is assured by the opening movement of the valve disk 41 which takes place immediately upon its spring breaking contact with the tank bottom. After replacement of the device, liquid may enter the body only through the restricted opening 42, and this is of advantage in that I thereby render the float less sensitive to fluctuations in response to repeated sloshing or surging of the liquid consequent upon jolting or movement of the tank. It may further be desirable to place graduations upon the outer side of the device, as indicated in Fig. 4. If such graduations read in terms of gallons, a convenient gauge will be afforded to the user, it merely being necessary that the device be taken out from the tank to observe the wet line thereupon.

I claim:

1. In combination with a receptacle having a screw-threaded filling spout, a chambered head formed for threaded connection with the spout, a slip ring on the head having a finger extending into the chamber thereof, an alarm device including a self-contained operating mechanism positioned within the head chamber and adapted to operate when the slip ring is rotated to present the finger in one position but not otherwise, and means extending from the head inwardly of the receptacle, including a float, and a connection therefrom to the operating mechanism adapted to permit functioning thereof only when the liquid level has descended to a predetermined point, substantially as described.

2. In combination with a liquid receptacle having a filling opening, a closure head removably fitted thereto, a bell having a self-contained operating mechanism positioned on the outer head side, guiding means removably fitted to the under head side and adapted to extend into the receptacle, and float controlled means slidably associated with said guiding means and having a part extending to the bell operating mechanism adapted to control the action thereof, said part being freely disengageable from the bell operating mechanism to facilitate removal of the guiding means from the closure head, substantially as described.

FRANK R. PROCUNIER
